EXPANSIBLE LINK CHAIN FOR A BRACELET OR THE LIKE

Emil Rodriguez, New York, N. Y., assignor to
Jacoby-Bender, Inc., New York, N. Y., a corpora-
tion of New York

Application November 3, 1951, Serial No. 17,267

Term of patent 7 years

(Cl. D45—4)

To all whom it may concern:

Be it known that I, Emil Rodriguez, a citizen of the United States and a resident of New York, county and State of New York, have invented a new, original, and ornamental Design for an Expansible Link Chain for a Bracelet or the like, of which the following is a specification, reference being had to the accompanying drawing, forming a part thereof, in which:

Fig. 1 is a top view of the expansible link chain in contracted condition showing my new design, portions of the conventional connecting links visible at the ends of the chain being shown in broken lines;

Fig. 2 is a top view thereof in partially expanded condition, portions of the conventional connecting links being visible between the top links and shown in broken lines;

Fig. 3 is a top plan view on an enlarged scale of one of the individual links of the chain of Fig. 1;

Fig. 4 is a cross sectional view of the link of Fig. 3 taken along the line 4—4 of Fig. 3; and
Fig. 5 is a side elevational view of the link of Fig. 3.

I claim:

The ornamental design for an expansible link chain for a bracelet or the like, as shown and described.

EMIL RODRIGUEZ.
